His Attorney.

UNITED STATES PATENT OFFICE

HAROLD C. SINGLETON, OF SCOTIA, NEW YORK, ASSIGNOR TO GENERAL ELECTRIC COMPANY, A CORPORATION OF NEW YORK

PROTECTIVE DEVICE

Application filed October 13, 1926. Serial No. 141,397.

My present invention relates to protective devices and more particularly to devices adapted for use in connection with fluid fuel burning furnaces provided with automatic ignition. In the employment of such devices the automatic ignition sometimes fails to work, and as a result damage is caused directly or indirectly by the escape of the fuel.

It is one of the objects of my invention to provide means for automatically interrupting the supply of fuel to a burner when the automatic ignition fails.

The novel features which I believe to be characteristic of my invention are set forth in the appended claim. My invention itself, however, will best be understood from reference to the following specification taken in connection with the accompanying drawing in which Fig. 1 shows partly in elevation and partly in section an assembled oil burning furnace, electric driven blower and control means embodying the features of my invention, while Fig. 2 shows diagrammatically a circuit organization for effecting control of the electric motor and thereby the control of the fuel supplied to the furnace.

The furnace 1, indicated in Fig. 1 of the drawing, includes a combustion chamber 2 and a burner, not shown. A blower pipe or mixing tube 3 is connected at one end to the burner and at the other end to a blower 4 driven by an electric motor 5. The mixing tube 3 is connected to an oil supply through pipe 6, and when blower 4 is in operation, oil is drawn through pipe 6 and supplied to the furnace burner.

In order to control the supply of fuel to the burner a light sensitive cell 7, in the present instance a photoelectric cell, is mounted at the end of the mixing tube 3, which is remote from the furnace so that light from the flames may be directed on to the cell without causing it to be damaged by the heat of the furnace. The cell 7 and electric discharge device 8 controlled thereby are mounted in a container 9, which may be supported in any suitable manner at the end of the mixing tube.

The circuit arrangement whereby the supply of fuel to the burner may be controlled is

shown in Fig. 2 in which an alternating current source of supply is indicated at 10. Motor 5 is connected to the source 10 through one of the contacts 11 of a relay 12 and through a pair of parallel connected switches 13 and 14, one of which, 13, is of low resistance and the other of which, 14, is a high resistance thermostatic switch. Switch 13 is normally held in closed position by means of a spring 15. Relay 12 is energized from an alternating current source through a circuit comprising a secondary winding 16 of transformer 17, and a thermostatic switch 18 adapted to automatically open and close the motor circuit in accordance with the room temperature it is desired to maintain. Switch 13 is controlled by a winding 19 connected in the output circuit of the electric discharge device 8, the latter including the usual anode, filamentary electrode and control element or grid 20. The filamentary electrode is supplied with heating current from the transformer 17 and its circuit is completed through a contact 21 on relay 12 so that it will be energized or deenergized simultaneously with the energization and deenergization of motor 5.

The photoelectric cell 7 is connected to one of the secondary windings of transformer 17 and to the grid 20 in such a manner that when light from the burner is directed on to the light sensitive surface of the cell, a negative potential or bias will be supplied to the grid element 20. This potential is sufficiently high to prevent flow of current in the output circuit of the discharge device 8 and as a result switch 13 will be maintained in closed position by the action of the spring 15. If for any reason the burner flame should be extinguished the light sensitive cell 7 would become deenergized, the negative potential would be removed from the grid 20, and as a result current would flow in the output circuit of the discharge device 8 and energize coil 19 to open switch 13. Current would now flow to the motor 5 through the high resistance thermostatic switch 14, and after a period of time, depending on the setting of switch 14, the contacts of the switch would separate and one of them would be locked in open position by means of a latch 22. Thereafter, in order

to initiate operation of the motor 5, it would be necessary to manually unlatch switch 14. Normally, since switch 13 is of very low resistance compared to switch 14, the former will act as a short circuit for switch 14 so that practically no current will flow through the latter switch and it will remain in closed position during the normal operation of motor 5.

10 While I have indicated an arrangement for controlling the fuel supply by means of a blower motor, obviously a motor operated valve in the fuel supply pipe could be controlled instead of the blower if desired. The 15 invention is moreover not limited to oil burners but is equally adapted for use in gas burning furnaces. In the latter type of furnace, however, a valve in the supply pipe would be controlled rather than a blower as 20 in the present case.

21 What I claim as new and desire to secure by Letters Patent of the United States is:—

An oil burner construction comprising a fan housing having a projecting nozzle portion, an air tube secured to said nozzle portion and opening thereinto, a combustion chamber into which the other end of said air tube opens, means for supplying fuel to said air tube, a housing secured to said nozzle portion and opening thereinto in alignment with the ends of said air tube and a flame responsive device in said housing whereby said flame responsive device is exposed to direct radiations from the burner flame.

35 In witness whereof, I have hereunto set my hand this 12th day of October 1926.

HAROLD C. SINGLETON.
